Application December 2, 1938, Serial No. 243,622
 In Germany December 6, 1937

4 Claims. (Cl. 250—27.5)

My invention relates to electron valves and more especially to mixing valves, in which, in the path through which the electrons travel, two separate controlling means are arranged in series.

It is one object of my invention to provide an improved valve of this type.

Recent developments have shown that mixing valves, in which the modulator grid is arranged nearest to the cathode, are better suited for mixing purposes than those types of valves, in which the oscillator grid was the first grid from the cathode.

This may be due to the fact that the stability of frequency of this latter type of valves is greater and that in these valves practically no space-charge coupling arises. Moreover the electrical tolerances can be observed far more readily, since the electrode adjacent to the modulator grid is the cathode, so that these grids do not adjoin a virtual cathode. However, the type of valves mentioned above involves the drawback that, owing to the second control of the electron current, part of the electrons must turn round and flow in the direction towards the cathode, which involves the following disadvantages: the transit-time of the electrons in the direction toward the cathode, is comparatively great so that, when short waves are received, the space inside of the anode cannot be considered as a stationary potential space, so that the rule, according to which no electrons can be emitted by a negative grid, is no more valid. In consequence thereof the negative biased modulator grid becomes the source of an obnoxious grid current.

Also the following circumstances must be noted: The electrons emitted towards the cathode produce a space-charge between the acceleration grid and the modulator grid, whereby the first grid, which thus serves as the first control means, whenever its potential changes, presents considerable variations of capacity, while on the other hand the input impedance depending on the transit-time of the electrons becomes too small. Finally also the stability of frequency of the hexode valves was unsatisfactory, since the variations of voltage at the first control grid, owing to the electrons accumulating before the second control grid, bring about changes of capacity of this second grid.

The present invention concerns an electron valve which is adapted to obviate all these drawbacks. The essence of this invention consists therein that in an electron valve with double control occurring in series in the electron path the second control is effected with the aid of a means

which causes the electrons to be deflected, however not to be reversed. These deflecting means preferably have the form of metal rods or of metal plates extending radially in relation to the cathode axis. In a preferred embodiment of the invention apertures are formed in the anode plate, the axis of symmetry of which apertures as well as the axis of symmetry of the cathode extend in the plane of the deflecting plate mentioned above. I prefer so designing these apertures that the slope of the anode current, relative to the voltage of the first grid is as far as possible linearly connected with the voltage of the deflecting plate. This is arranged for the purpose of filtering the harmonics of an even order. I further prefer to arrange collecting screens in front of or in or to the rear of the apertures of the anode.

In the drawing affixed to this specification four embodiments of my invention are illustrated diagrammatically by way of example.

Fig. 1 is a diagrammatic showing of one embodiment of the invention, while

Figs. 2, 3 and 4 illustrate diagrammatically various modifications thereof.

Referring to the drawing, the cathode, in the modification shown in Fig. 1, is marked 1; 2 is a normal control grid (modulator grid), 3 a so-called acceleration grid having a positive potential, while 4 are the deflecting plates which render possible the second control (oscillator control). As shown in the drawing, these plates extend in the direction of travel of the electrons, so that the change of potential of the deflecting plates can only cause the electrons to change their direction, i. e., a deflection, however not a reversal of this direction. 5 is the anode formed with the apertures 15, while 6 are baffles.

The operation of this valve is substantially as follows: The electrons emerging from the cathode are subjected by the grid 2 to the first control which occurs in the usual manner. The role played by the acceleration electrode 3 is self-explanatory. The electrons thereafter reach the region in which the deflecting plates 4 are arranged. If the deflecting plate has a sufficiently positive potential, the electron current is constricted and in consequence thereof a considerable part of the current flows through the apertures 15 to the baffles 6. If now the potential of the deflecting plate 4 becomes correspondingly less positive, the flow of electrons is subdivided in two parts, which may then meet, all of them, the parts of the anode to the left or to the right of the apertures, without reaching the baffles. Obviously the fact that the electrons are not re-

versed and that, owing to the positive voltage of the deflecting plates, they cannot accumulate in the discharge space, does away with all drawbacks mentioned above, which are connected with these phenomena.

Since the deflecting plate controls the anode current and consequently the slope of the anode current with regard to the change of voltage of the grid 2, I obtain, when feeding to the deflecting plate 4 the local oscillation and to the grid 2 the oscillation to be received, a multiplicative mixing.

In the embodiment of my invention illustrated in Fig. 2, similar reference numerals designate similar parts. The grid 7 is an acceleration grid, which serves for electrical screening and therefore preferably has a positive potential. 8 is a suppressor grid having a negative potential, so that it may for instance be electrically connected with the cathode. 9 is the gridlike structure which serves for preventing the mutual secondary emission between the anode and the collecting screen. I prefer providing this grid 9 with a mesh-like arrangement in order to prevent any accumulation of electrons. It should be noted that in the valves according to my invention the anode current cannot merely be drawn from the anode, but also simultaneously from the anode and the baffles; in that case the two parts should be connected in a push-pull circuit. 11 is a particularly useful form of the grid bars of the first grid, which enable the entire bundle of electrons to pass through the apertures of the anode without impinging on the anode. I can obtain this effect by means of rods of a corresponding thickness and/or by means of screening plates.

In a third embodiment of the new valve illustrated in Fig. 3 the two deflecting plates 4 are not directly connected with each other. Here the deflecting plate may be controlled in push-pull in order to filter the harmonics of an even order. For this purpose the anodes should be arranged as shown in Fig. 3, where the anode plates are split up at 10 and 10' and the two parts 5a and 5b of the anodes are electrically connected with the opposite baffles, 5a being connected with 6b, 5b with 6a. Thus the two parts of the anode are connected in push-pull. In a particularly useful embodiment of the valve according to this invention also an oscillator system is arranged in the same tube, and the two systems may have the cathode in common. In such composite tubes the anode of the oscillator systems may also be electrically connected with the deflecting plates.

The embodiment according to Fig. 4 is intended to improve the spreading. To this end the ar-

rangement of parts above described is provided for six or eight times on the circumference of the electrode system.

Fig. 4 shows a fourfold arrangement in a valve 5 which otherwise corresponds to the one shown in Fig. 1, but in which, instead of two, four deflecting plates 4 and four baffles 6 are provided, while the anode consists of four parts 25 separated by four apertures 15. On principle this 10 arrangement acts similarly as the one shown in Fig. 1, but, owing to the greater number of control organs, its efficiency is greater.

Various changes may be made in the details 15 disclosed in the foregoing specification without departing from the invention or sacrificing the advantages thereof.

I claim:

1. An electronic mixing valve comprising in combination, a cathode, a first control means being a space-charge control and including a grid 20 surrounding said cathode and adapted to receive the signal voltages to be amplified, a second control means comprising a positively charged member arranged in series with said first control means in the electron stream and adapted to receive the local oscillator voltages whereby to deflect the electrons without reversing their direction of flow, an anode comprising an aperture and a baffle arranged opposite said aperture surrounding said second control means but spaced 25 from said positively charged member in radial direction with respect to said cathode, said grid including grid bars adapted to permit the entire electron current to pass said aperture.

35 2. The electron valve of claim 1, in which the second control means is a metallic deflecting plate radially disposed with relation to the cathode axis, and the anode is a plate formed with an aperture, one axis of symmetry of which as well 40 as the axis of symmetry of the cathode extend in the plane of the deflecting plate.

3. The electron valve of claim 1, in which the second control means is a metallic deflecting plate radially disposed with relation to the cathode axis, and the anode is a plate formed with an aperture, one axis of symmetry of which as well 45 as the axis of symmetry of the cathode extend in the plane of the deflecting plate, a baffle being arranged near the aperture and a mesh-like grid between the anode and the baffle.

50 4. The electron valve of claim 1, in which the second control means is a metallic deflecting plate radially disposed with relation to the cathode axis, while a screen grid having a positive potential is arranged between the anode and the deflecting plate.

ERNÖ WINTER.
